UNITED STATES PATENT OFFICE.

WALTER E. WAHRA, OF MILWAUKEE, WISCONSIN, ASSIGNOR TO MILWAUKEE NET COMPANY, OF MILWAUKEE, WISCONSIN, A CORPORATION OF WISCONSIN.

FLY-NET FOR HORSES.

1,078,022.

Specification of Letters Patent. Patented Nov. 11, 1913.

Application filed March 16, 1912. Serial No. 684,160.

To all whom it may concern:

Be it known that I, WALTER E. WAHRA, a citizen of the United States, residing at Milwaukee, county of Milwaukee, and State of Wisconsin, have invented new and useful Improvements in Fly-Nets for Horses, of which the following is a specification.

My invention relates to improvements in fly nets for horses, and it pertains to that 10 class which comprise a plurality of longitudinal bars and transverse cords, which longitudinal bars may be either braided, woven or formed of two pieces of ordinary webbing or other material, stitched together.

15 The object of my invention is more especially to provide a simple and efficient means for preventing the transverse cords from sliding through the longitudinal bars, my device thus retaining said longitudinal bars 20 at uniform distances apart and in their proper relative position to each other.

My invention is further explained by reference to the accompanying drawings, in which—

25 Figure 1 represents a plan view of my device as used in connection with longitudinal braided bars. Fig. 2 represents my device as used in connection with woven bars. Fig. 3 represents the retaining device as used in 30 connection with bars formed of two pieces of ordinary woven fabric or other material secured together by a longitudinal series of stitches. Fig. 4 is a detail view illustrating the relation of the retaining cords with the 35 transversely arranged cords.

Like parts are identified by the same reference numerals throughout the several views.

1 represents the longitudinal bars as formed of braided material.

40 2 represents the longitudinal bars as they appear when interwoven, and 3 represents the longitudinal bars as formed of two strips of woven fabric or other material secured together by a longitudinal series of stitches 45 4, 4 upon the respective sides of the retaining cords 5.

6 represents the transversely arranged cords of a net of ordinary construction.

Novelty of invention is herein predicated more especially upon the use of the cord or 50 cords 5 for retaining the longitudinal bars 1, 2 and 3 in place upon the transversely arranged cords 6. The longitudinal cords 5 are securely retained in their relative position to the transverse cords 6 by being inserted 55 between the strands of said cords, regardless of the form of the longitudinal bars with which they are used. In all cases the longitudinal cord or cords 5 are adapted to be inserted between, or between and also 60 around, the strands of the transverse cords 6 throughout the entire body of the net, regardless of the construction of the longitudinal bars. When the longitudinal cord or 65 cords 5 are used with that class of longitudinal bars 2 shown in Fig. 2, said cord or cords 5 may be woven in and form a part of the mesh of said bars. When, however, the longitudinal fastening cord or cords 5 are used with that class of longitudinal bars 70 shown in Fig. 3, said cords are retained in place between the upper and lower members 9, 9, said members being secured together by a longitudinal series of stitches 4, 4. The fastening cord or cords 5 may also be connected 75 with the transverse cords 6 at intermediate points between the longitudinal bars, and a knot may, if desired, be formed in said cords 5 around the transverse cords 6 at one or more points of contact, as shown 80 in Fig. 1.

Having thus described my invention, what I claim as new, and desire to secure by Letters Patent, is—

1. In a fly net for horses, the combination 85 with sets of longitudinally extending bars of fabric and a set of transverse bar-connecting cords crossing the bars of fabric and secured thereto, of a series of longitudinally disposed retaining cords each extending between the strands of the transverse cords, some of said retaining cords being secured to the respective bars between the transverse cords, substantially as described.

2. In a fly net for horses, the combination 95 with sets of longitudinally extending bars

of fabric and a set of transverse bar-connecting cords crossing the bars of fabric and secured thereto, of a series of longitudinally disposed retaining cords each extending between the strands of the transverse cords, some of said retaining cords being secured to the respective bars between the transverse cords, and other of said retaining cords ex-

tending parallel to the bars in the spaces between the bars, substantially as described. 10

In testimony whereof I affix my signature in the presence of two witnesses.

WALTER E. WAHRA.
